CLAIM

The ornamental design for a fishing tackle tray box carrier as shown and described.

DESCRIPTION

FIG. 1 is a perspective view of a front side of the fishing tackle tray box carrier showing our new design.

FIG. 2 is a perspective view of a top side thereof.

FIG. 3 is a perspective view of a bottom side thereof.

FIG. 4 is an elevational view of the front side thereof.

FIG. 5 is an elevational view of a back side thereof.

FIG. 6 is an elevational view of a first lateral side thereof.

FIG. 7 is an elevational view of a second lateral side thereof.

FIG. 8 is a plan view of the top side thereof.

FIG. 9 is a view of the bottom side thereof; and,

FIG. 10 is another perspective view of the front side thereof, showing finishing tackle tray boxes contained within the fishing tackle tray box carrier.

The dash-dash broken lines depict environmental subject matter that form no part of the claimed design.
